UNITED STATES PATENT OFFICE.

JOHN F. FARRINGTON, OF NEW YORK, N. Y., ASSIGNOR TO WESTERN ELECTRIC COMPANY, INCORPORATED, OF NEW YORK, N. Y., A CORPORATION OF NEW YORK.

RADIOSIGNALING.

Application filed November 20, 1922. Serial No. 601,975.

This invention relates to carrier wave signaling and particularly to repeating systems for amplifying at intermediate points the signal transmitted between two radio stations.

An object of the invention is to provide a system for two-way radio repeating, and to prevent at the repeater station the useless and wasteful circulation of energy which attends the condition of "singing."

An additional object is to provide a radio repeating system which is effective to prevent "singing" under conditions requiring the use of a single antenna for transmitting and receiving or where physical conditions are otherwise especially conducive to interference between the transmitting and receiving circuits.

A radio repeating station, in general, comprises an antenna structure for receiving a radio wave from a distant transmitting station or from another repeating circuit, circuits for amplifying the received wave, and an antenna structure for radiating the amplified wave. Considerations of economy usually require that the two antennæ be in close proximity or be combined in a unitary structure. In either of these cases, a potential "singing" circuit is provided by the amplifying circuits and the connection between the transmitting and receiving antennæ which may, as in the former case, be an ether link or, as in the latter case, a conductive connection. Singing occurs when the energy loss through the closed singing circuit is exceeded by the amplification. Since singing is detrimental to a faithful repetition of the signal at the repeater and must be avoided, the efficient use of the repeater, which obviously depends on the amplification capable of being secured, is accordingly limited by the critical conditions imposed by the liability of the circuits to sing.

Methods for increasing the effectiveness of the repeater stations have accordingly been directed toward increasing the loss or attenuation of the circulating energy in the singing circuit or, as explained in a different way, towards increasing the impedance of the singing circuit to the circulating current. To this end the expedient has been used of directive transmission and reception at the repeater. Electrical balance between the transmitting and receiving antenna cir-

cuits has sometimes been used, either alone or supplementary to other means. A common expedient has been to change the frequency of the received wave at some point in its passage through the repeater and to radiate it at its changed frequency. Since, in this arrangement, the receiving antenna is tuned to a frequency different from that transmitted from a repeater, it is incapable of efficient reception thereof and the closed loop through which singing tends to occur is given such a high attenuation as to prevent singing. Where a common transmitting and receiving antenna is used an effect analogous to that secured with a two-antenna arrangement may be secured by inserting a trap or anti-resonant circuit in the receiving circuit tuned to the frequency of the transmitted wave.

In applicant's invention, singing is prevented by changing the carrier frequency, but the circuits for accomplishing this are quite different from those of the prior art. Considered broadly, applicant's method involves the following sequence of operations. The incoming signal modulated wave is combined with a wave from a local source to produce a difference frequency wave modulated in the same manner as the received wave. This wave is detected to produce the signal component which is then used to modulate an outgoing wave having a frequency differing from that of the incoming wave, the resultant wave being transmitted either from an individual antenna or from an antenna used in common for transmitting and receiving. The outgoing wave is preferably built up by first modulating an intermediate frequency wave with the signal and combining the resultant wave with the wave from a local source to produce the sum frequency component. The receiving and transmitting operations are accordingly quite similar to the methods of receiving and transmitting identified by the term "successive detection" and "successive modulation" and have the usual advantages which attend the use of arrangements of these general types, namely, amplification and increased selectivity (and hence increased discrimination against atmospheric disturbances and against undesired signal waves).

By reason of the change of frequency of the carrier wave during its passage through the repeater, conditions are made unfavor-

able to singing as in the other example of this general type of repeater system. An additional impediment to singing which is not found in the prior systems results on account of the particular type of receiving arrangement, since any combination frequency which would result from interaction of the received and transmitted waves may be made different from the normal auxiliary frequency, resulting from the combination of the received wave with the wave from the local source, and accordingly, is inefficiently transmitted by the receiver circuits which are tuned to the normal auxiliary carrier wave.

In the preferred embodiment of the invention, a single local source is used for the first step of detection and the final step of modulation, that is, the wave from this source is combined with the normally received wave to produce a modulated auxiliary frequency carrier wave and is itself modulated by a lower frequency wave which, in turn, is modulated by the signal. The modulation of the outgoing wave effectively increases its frequency by the signal modulated wave frequency. The singing circuit is accordingly given a high impedance for the circulating current by each of the two means described in connection with the general case, namely, by circuits capable of discriminating between the incoming and outgoing frequencies and by the auxiliary frequency tuning, which discriminates against the undesired combination frequency. The preferred arrangement is especially advantageous under unusual conditions of space limitation, since use may be made of the interference from the transmitting circuit to establish the auxiliary frequency wave. In a practical case, this arrangement permits efficient repeater operation when a single antenna is used for transmitting and receiving, reliance being had principally on the effect of auxiliary frequency tuning to prevent singing.

It should be noted that the successive modulation method used at the repeater makes possible the effective use of the successive detection method at the terminal receiving station with its attendant advantages of increased amplification and selectivity, an important feature of applicant's invention.

Among the further objects and features of the invention which will be apparent from the reading of the following description is that of providing efficient and simple forms of circuits for carrying the principles of the invention into effect.

In connection with the detailed description reference will be made to the accompanying drawings wherein Fig. 1 illustrates a preferred form of the invention in which a single local source is used for the first step of detection and the final step of modulation,

Fig. 2 illustrates a system similar to that of Fig. 1 but arranged for two-way operation and Fig. 3 illustrates the terminal arrangement which may be used at a station designed to cooperate with the repeater of either Fig. 1 or Fig. 2.

In the description and drawing certain of the elements will, for convenience, be identified by reference letters which are suggestive of their functions, elements of the same kind being distinguished from each other by subscripts. For example, the letters D, M, A, and F will be used to represent respectively a detector, modulator, antenna, and filter. It will be assumed with respect to each of the figures that it is desired to communicate between two stations sending out waves of frequency f_1 and f_4 , which will be assumed for convenience to be respectively 700,000 and 720,000 cycles. These waves are assumed to be modulated, respectively, by speech or other audible frequency signals S_1 and S_4 . Although a single repeating station will be assumed, the extension of the system so as to include any number of such stations will be obvious.

In the drawing, except where otherwise indicated, the frequency labeling of the filters refers to transmitted, rather than to suppressed frequencies. As will be explained later, these filters may be alternatively adapted for the transmission of various other combinations of frequencies than that indicated, each of which will, however, involve certain of the frequencies in the combination actually indicated in the drawing and no additional frequencies produced in the system, i. e. such combinations will include merely a lesser number of the frequencies indicated. Frequency labels for these alternative combinations are not used since they would tend to greatly confuse the illustration of the invention.

Referring to Fig. 1, which discloses circuits for one-way repeating from a station transmitting a frequency f_1 to a station transmitting frequency f_4 , the antenna A with the branched circuit 5 and parallel circuits through 3 to ground constitutes, in combination with the reactance of the generator G, a receiving conductor which is tuned to the incoming carrier frequency f_1 . The legend $f_1 \pm S_1$ indicates that the received wave comprises the unmodulated component f_1 and one or both of the side bands $f_1 + S_1$ and $f_1 - S_1$. In the analysis that follows it should be understood that this double sign wherever occurring signifies that either or both of the side bands indicated by the two signs may be present.

The local source G is used in the first of the two steps of detection to step down the received carrier frequency and in the final step of modulation to step up the intermediate carrier frequency to the value required

for transmission. Obviously individual antennæ may be used for receiving and transmitting although a single antenna is shown. In order that the antenna may be doubly tuned so as to respond to the transmitted carrier frequency as well as to the receiving carrier frequency the branched circuit 5 is made an effective open circuit for waves of the transmitted frequency by the insertion 5 of the circuit 2, which is anti-resonant at the mean frequency of the transmitted carrier wave, the aerial portion of the antenna A with the transmitting circuits being tuned to resonance at said frequency. Since the 10 transmitted wave is a successively modulated wave of the radio carrier frequency f_2 of the source G modulated by a signal modulated wave, the mean frequency of the transmitted wave would be f_2 if both side bands of frequency f_2 are transmitted. If a single side band is transmitted the antenna would be tuned to a frequency differing from f_2 by the mean signal modulating frequency. Although circuit 2 is substantially anti-resonant at frequency f_2 sufficient energy of that frequency is transferred to circuit 5 from generator G to enable the generator to accomplish its function as a local receiver source. For this purpose circuit 2 may, if necessary, be slightly detuned. A separate transmitting antenna may be used if desired in which case the local energy for reception may be transmitted to the receiver circuit by radiation as is shown, for example, in U. S. 25 patent to Farrington, 1,495,470, May 27, 1924. Frequency f_2 may be higher or lower than f_1 . It is assumed to be 750,000 cycles.

The received energy and the energy from the generator G is transmitted through circuit 4 or any other selective circuit to high frequency detector D. The circuit 4 is adjusted to resonance with currents of frequency f_1 . The tuning of this circuit is sufficiently broad, however, to permit a certain 30 amount of current of frequency f_2 to pass therethrough. Detector D and the other detectors to be described may each be of any of the types commonly used for operating on a high frequency modulated wave to produce 35 the modulating component. A vacuum tube detector is shown in each case. The action of such a device in combining simultaneously impressed waves is explained in considerable detail in British Patent No. 102,503.

50 Among components resulting from detection will be the lower side components having the difference frequencies $f_2 - f_1$ and $(f_2 - f_1) \pm S_1$. Assuming speech modulation, the essential speech frequencies being included in the range between 200 and 2000 cycles, these component side bands would comprise respectively, frequencies from 48,000 to 49,800 cycles and from 50,200 to 52,000 cycles. These components are selected and 55 transmitted to auxiliary frequency detector D₁ by a band filter F which may be of the type described in pages 312 to 314, inclusive, of a paper by Colpitts and Blackwell, Carrier Current Telephony and Telegraphy, vol. 40, No. 4 of the Proceedings of the Institute of Electrical Engineers. 70

Detector D₁, which may be similar in all respects to D, operates upon the difference frequency waves selected by the band filter to give the signal frequency component S₁. 75 This signal component is selected by low pass filter F₁, which cuts off at the upper limit of voice frequency, and impressed upon modulator M to modulate intermediate carrier wave of frequency f_3 supplied by a local source G₁. If desired the modulator M may be of the well-known balanced type described in the article (Carrier Current Telephony and Telegraphy) referred to above, in which modulation would be attended by elimination of the unmodulated component of frequency f_3 . 80

A band pass filter F₂, which may be of the same type as F, suppresses the signal component S₁ and transmits to modulator M₁ either or both of the side bands $f_3 \pm S_1$, in either case with or without the unmodulated component of frequency f_3 . Generator G supplies a wave of frequency f_2 to modulator M₁ which may be of the type illustrated by M but is preferably of the constant current type described at page 360 of a paper by Craft and Colpitts, Radio Telephony, volume 8, No. 3, Proceedings of American Institute of Electrical Engineers. 90

This final step of modulation yields a successively modulated wave of radio carrier frequency f_2 and an intermediate carrier frequency f_3 . The repeating operation accordingly is, in effect, an amplification of the received wave and a retransmission with the new carrier frequency $f_2 - f_3$, or $f_2 + f_3$, the wave of this frequency being modulated by the signal S₁. If a wave of frequency f_3 is impressed on modulator M₁ the retransmitted wave contains the unmodulated component $f_2 \pm f_3$ as well as the side bands so that the signal S₁ may be detected at the terminal, or another repeating, station, by a single detecting operation in the ordinary way. In 105 this case the unmodulated component f_2 would be of no use at the terminal station and, with one side band if desired, may be suppressed before transmission with consequent economy of energy and frequency 110 range. In this case the unmodulated component may be supplied to the circuit 5 or 4 by a direct connection to generator G through circuits 6 and 7, switch 8 being thrown to the left, or by a separate source 9 through circuit 7, the switch being thrown to the right. If recourse is not had to these means for impressing a current directly on circuit 4, the switch is, of course, left in neutral position. In the alternative that the 115 120 125 130

components necessary for detection of S_1 by a single operation are not present, or even if these components are present, detection may be accomplished by a system of successive double detection as will be explained in detail later. In general, this latter method would be preferred on account of the increased selectivity afforded thereby. In the specification and claims the term "carrier frequency" when referring to a successively modulated wave will mean, consistently with the above, that frequency which when combined with such successively modulated wave will yield the signal in one detecting step. In the case of a successively modulated wave produced by modulating an intermediate frequency wave by a signal wave, and modulating a high frequency wave by the resultant wave, the carrier wave will have a frequency equal to the sum or difference of the frequencies of the high and intermediate frequency waves. Whether the sum or difference is taken will be indicated by the context.

In a system of the type described the combination frequency wave resulting from interaction in detector D of the wave transmitted from the repeater and the wave incoming from the distant station transmitting carrier frequency f_1 would result in a spurious auxiliary frequency which would differ by f_3 from the desired auxiliary frequency for which the auxiliary circuit including filter F is adjusted. Any portion of this wave transmitted through the filter after detection by D_1 will give a component $f_3 \pm S_1$ which will not pass filter F_1 . It is readily seen that f_3 must be given a sufficiently high value so that $f_3 \pm S_1$ can be separated from S_1 by filters F_1 and F_2 . f_2 should have such a value that frequencies $f_2 - f_1$ and $f_2 - f_1 \pm S_1$ can be separated from S_1 . 5,000 cycles has been suggested as a practicable value for f_3 . It is to be noted that the successive detection arrangement in this system makes possible the use of a smaller frequency difference ($f_2 \pm f_3 - f_1$) between incoming and outgoing wave frequencies than is possible with systems of the prior art on account of the increased discrimination against undesired frequencies, which is an important advantage of the successive detection principle, wherever applied. Further, the transmitting source supplies the local oscillations for receiving and accomplishes every purpose otherwise secured in successive detection and successive modulation with two local sources. In the alternative arrangement in which a separate local source is used for transmitting and receiving, there would be no special relation between the normal auxiliary carrier frequency for which F is adjusted and the spurious auxiliary frequency established by interaction of the transmitted and received

waves and the difference between these two frequencies could be made much greater than f_3 .

Fig. 2 illustrates an application of the principle to two-way communication. Assume that in addition to the one-way communication of Fig. 1 there is an opposite communication from a station sending out waves of a carrier frequency f_4 and signal frequency S_4 .

When the two oppositely directed channels are simultaneously in operation, waves of frequencies f_1 , $f_1 \pm S_1$ and f_4 , $f_4 \pm S_4$ are impressed on the receiving antenna of the repeater. The antenna circuit containing the generator G is tuned to transmit current of frequency f_2 and a side band of that frequency, while the branch circuit 5, together with the transmitter circuit is broadly tuned to frequencies f^1 and f^4 .

Assuming f^4 to be 720,000 cycles, detection by D will yield, among other components, the combination frequencies $f_2 - f_1$ and $f_2 - f_4$ and these frequencies modulated by their respective signals. With the values assumed these combination frequencies will have the values, respectively, of 50,000 and 30,000 cycles. The former with its signal side bands will be transmitted through circuits F_1 , D_1 , F_1 , M and F_2 as in Fig. 1. The latter with its side bands in a similar manner will be transmitted through circuits F_3 , D_2 , F_4 , M_2 and F_5 . The signal modulated intermediate carrier waves resulting from the last modulating operation are impressed together by circuit 1 on modulator M_1 . The transmitted wave from said modulator is a double modulated wave having two sets of intermediate carrier and signal frequencies. If the values of the intermediate carrier frequencies f_3 and f_5 are properly selected, 5,000 and 10,000 cycles respectively, in the assumed case, the wave received at the terminal station can be put through the detecting operation to be described and the signal components S_1 and S_4 separated.

Although in the case in which the intermediate carrier frequencies are transmitted to M_1 , it is possible to produce a signal at the terminal station by a single detecting operation, the preferred arrangement involves the use of successive detection and, in particular, the triple detection arrangement of Fig. 3. The station of Fig. 3 transmits a modulated wave of carrier frequency f_1 , to which the antenna A and transmitting circuits are tuned. The station receives two sets of double modulated waves each having the radio carrier frequency f_2 , and one having an intermediate carrier frequency f_5 and signal frequency S_4 , and the other having the intermediate carrier frequency f_3 and signal frequency S_1 , the latter being the wave originally transmitted from the station of Fig. 3 and retransmitted back to that station

from the repeater. Antenna and branched circuit 5 are tuned broadly to include these frequencies. If both side bands of f_2 are transmitted, the frequencies will range between 762,000 and 738,000 cycles. It is entirely immaterial, so far as the receiving function is concerned, whether one or both side bands, either of frequency f_1 or of the intermediate carrier frequencies, are transmitted, from the repeater.

The output of the detector D_3 will have, among other components, difference frequencies having values of 50,000, 50,000 plus and minus 7,000 and 50,000 plus and minus 12,000 cycles, taking the maximum value of speech frequencies assumed as representing all speech frequencies. Since it is desired to receive signal S_4 , filter F_6 is designed to pass currents of 38,000 and 62,000 cycles or it may be designed to pass only one of the frequencies 38,000 or 62,000, if desired or if only one of such frequencies is transmitted to the terminal station. If only one of these frequencies 38,000 or 62,000 is transmitted, the filter can be designed to pass currents of frequencies between 58,000 and 62,000 cycles or, if a single signal bearing side band is used, it can be designed to pass currents of frequencies between 58,000 and 60,000 cycles or between 60,000 and 62,000 cycles and discrimination is secured at this point from the undesired intermediate frequency wave modulated by signal S_1 . The product of the auxiliary detection by D_4 includes waves of frequencies $10,000 \pm S_4$ and $5,000 \pm S_1$ if filter F_6 passes both intermediate frequencies f_3 and f_5 . In this case, the component $10,000 \pm S_4$ is selected by filter F_7 , and the signal frequency S_4 is obtained from the output of the low frequency detector D_5 , after selection by filter F_8 if desired. If the filter F_6 is designed to suppress all components within the range 38,000 to 62,000 except a single unmodulated component such as 60,000 and accompanying side bands 60,000 + S and 60,000 - S , the undesired intermediate carrier, signal modulated, wave, i. e. all frequencies within the range 50,000 - 5,000 - S and 50,000 + 5,000 + S would be eliminated by filter F_6 , and the additional stages of selection, although preferably used, would not be necessary for discrimination from the other signal modulated, intermediate carrier, frequency. If current of frequency f_5 is not transmitted from the repeater station as a modulation of f_2 , it must be supplied from a local source, as generator G_4 . If this component is transmitted the local source G_4 may be omitted.

The result of the final stage of detection and the first stage of modulation both at the repeater may be considered a change in the auxiliary carrier frequency. It is obvious that an equivalent change may be secured without detection of the signal com-

ponent and the invention is to be understood as covering broadly any method or instrumentality for accomplishing this change.

The novel features believed to be inherent in the invention are defined in the appended claims.

What is claimed is:

1. The method of radio repeating which comprises transmitting a carrier wave, receiving a signal modulated radio wave having a different frequency, combining a portion of the transmitted wave with the received wave to produce an auxiliary modulated carrier wave, selecting said auxiliary modulated carrier wave, changing the frequency of said auxiliary carrier wave, and modulating the transmitted wave with said changed frequency auxiliary modulated wave. 75

2. The method of radio repeating which comprises transmitting a carrier wave, receiving a signal modulated radio wave having a different frequency, combining a portion of the transmitted wave with the received wave to produce an auxiliary modulated carrier wave, selecting said auxiliary modulated carrier wave, detecting the auxiliary modulated wave to produce the signal wave, modulating a sub-carrier wave with said signal wave, suppressing the signal component and modulating said transmitted wave with the sub-carrier modulated wave. 90

3. The method of two-way radio repeating which comprises transmitting a carrier wave, receiving a plurality of modulated radio waves having frequencies different from each other and from the frequency of the transmitted wave, combining a portion of the transmitted wave with the received waves to produce a plurality of auxiliary carrier modulated waves, selecting and detecting each of said auxiliary carrier waves to produce their respective modulating components, modulating a sub-carrier wave with each of said modulating components, suppressing each of said modulating components, and modulating the transmitted wave with each of said sub-carrier modulated waves, each of said sub-carrier frequencies being so chosen that modulation with either of the signal frequencies will result in combination frequencies only without the signal frequency range, the sub-carrier frequencies differing from each other by an amount such that their modulated components can be separated, and the radio transmitting carrier and received carrier frequencies differing sufficiently so that modulation by said sub-carrier or signal frequency waves will 105

110

115

120

125

give frequencies only without the signal frequency range.

4. A radio repeater comprising in combination a receiving conductor resonant to the frequency of the incoming wave, a local source, means for combining energy from the 130

- local source with the incoming wave to produce an auxiliary frequency wave, selecting means for said auxiliary frequency wave, means for changing the frequency of the auxiliary frequency wave, means for modulating a portion of the energy from said local source with said changed frequency auxiliary wave, and means for selectively transmitting said modulated wave.
5. A radio repeater comprising a receiving conductor resonant to the frequency of an incoming modulated radio wave, a local source, means for combining energy from the local source with the incoming wave to produce an auxiliary frequency modulated carrier wave, selecting means for said auxiliary frequency wave, detecting means for the auxiliary frequency modulated carrier wave, a sub-carrier frequency source, means for modulating the wave from the sub-carrier source with the detected modulating component, means for suppressing the unmodulated component, and means for selectively transmitting said sub-carrier modulated wave as modulations of a radio carrier wave, the frequencies of the waves from said sources and of the transmitted wave being so chosen that the sum of the frequencies of the radio and sub-carrier wave is different from that of the received wave and of such value that interaction with the incoming wave will result only in combination frequencies different from that for which said selective auxiliary frequency circuit is adjusted.
10. 6. A radio repeater, comprising a receiving conductor resonant to the frequency of an incoming modulated carrier wave, a transmitting source, a transmitting conductor resonant to the wave from said transmitting source, means for combining a portion of the energy from said source with the received wave to give an auxiliary frequency modulated carrier wave, selecting and detecting means for said auxiliary frequency carrier modulated wave, a sub-carrier frequency source, means for modulating the wave from the sub-carrier source by the detected modulating component, and means for selectively transmitting said sub-carrier modulated wave as modulations of the wave from said transmitting source, the frequencies of the waves from said sources being so chosen that the sum of the frequencies of the radio and sub-carrier wave is different from that of the received wave and of such value that interaction with the incoming wave will result only in combination frequencies different from that for which said selective auxiliary frequency circuit is adjusted.
15. 7. The combination as defined in claim 6 in which the receiving and transmitting conductors are combined to form a single double tuned antenna for receiving and transmitting,
20. 8. In combination a receiving conductor resonant to the frequency of the incoming wave, a local source, means for combining energy from the local source with the incoming wave to produce an auxiliary frequency wave, a circuit connected thereto including a selecting means for said auxiliary frequency wave, a second circuit connected with the above mentioned circuit including means for producing a wave, means for modulating therewith a portion of the energy from said local source and means for transmitting said modulated wave.
25. 9. The method of radio repeating which comprises generating a wave, receiving a signal modulated radio wave having a different frequency, combining a portion of said generated wave with the received wave to produce an auxiliary modulated carrier wave and utilizing said auxiliary modulated carrier wave and said generated wave to produce a modulated carrier wave whose frequency is different from that of the generated wave, and transmitting said finally modulated wave.
